FIGURE 1 is a top perspective view of an automobile with roller top cover embodying my new design,

FIG. 2 is a rear top perspective view of the automobile with the roller top cover extended from one roller to the other and over an upwardly extended frame structure, the rear roller having been raised from the slot in the tailgate,

FIG. 3 is a side elevational view with the cover extended from the front roller and over the front and intermediate seats to the partially closed position shown,

FIG. 4 is a side elevational view wherein the cover has been pulled rearwardly from the front casing over the front seat and to the partially closed position shown,

FIG. 5 is a side elevational view wherein the top cover has been pulled forwardly from the rear casing and over the rear seat,

FIG. 6 is a side elevational view wherein the two top covers are used and pulled respectively from the front and rear casing to the intermediate supports,

FIG. 7 is a top perspective view with the intermediate and rear seats collapsed into the floor, the rear cover casing retracted into the tailgate with the tailgate down and looking into the rear of the automobile, and

FIG. 8 is a side elevational view with slightly modified doors and showing the top cover pulled from one of the cover casings to the fully closed position shown.

This application is a continuation-in-part of my previously filed applications Ser. No. D. 87,561 and D. 87,569, both filed Oct. 18, 1965 and now abandoned.

I claim:

The ornamental design for an automobile with roller top cover, substantially as shown and described.
